UNITED STATES PATENT OFFICE.

DANIEL S. EVERETT, OF JORDAN, NEW YORK.

POWER-JACK FOR AUTOMOBILES.

1,212,200.

Specification of Letters Patent. Patented Jan. 16, 1917.

Application filed March 15, 1916. Serial No. 84,458.

To all whom it may concern:

Be it known that I, DANIEL S. EVERETT, a citizen of the United States, and resident of Jordan, in the county of Onondaga and State of New York, have invented certain new and useful Improvements in Power-Jacks for Automobiles, of which the following is a specification.

The present invention relates to automobile-jacks of the type in which a wheel of an automobile is caused to engage a power-wheel in order to transmit power from the automobile to a suitable power-shaft for the purpose of driving farm machinery and the like, and an object of the invention is to provide a construction in which a runway leads to the power-wheel and, after the engagement of the wheel of the vehicle with the power-wheel, is automatically moved out of engagement with the vehicle-wheel by the latter so that the runway will not interfere with the turning of the vehicle-wheel.

Another object of the invention is to provide a supporting means for the vehicle which may be brought into coöperation with the vehicle while the wheel of the vehicle engages the runway and the power-wheel.

Still another object of the invention is to provide a supporting means for the vehicle which may be quickly moved to and from supporting position.

A further object of the invention is to provide an improved mounting before the runway.

To these and other ends, the invention consists in certain parts and combinations of parts all of which will be hereinafter described, the novel features being pointed out in the appended claims.

In the drawings: Figure 1 is a side-view of the jack showing the vehicle-wheel in engagement with the runway and the power-wheel and the supporting means adjusted to engage the vehicle but not locked in such position; Fig. 2 is a side-view showing the runway shifted out of engagement with the vehicle-wheel and the supporting member locked in supporting position; Fig. 3 is a plan-view of the jack; Fig. 4 is a section on the line *a—a*, Fig. 1; and Fig. 5 is a sec-

tion of a modification in which the power-shaft is provided with two power-wheels for engaging the two rear wheels of a motor vehicle, and the jack is also provided with two runways and two supporting devices. 55

In the illustrated embodiment of the invention the jack comprises a main frame preferably formed of two angle bars 1 connected by cross-pieces 2, 3 and 4, the latter being formed to elevate one end of the frame. 60 Also connecting the cross-pieces is a power-shaft 5 provided with a pulley 6 from which the power is obtained. On this power-shaft 5, between the bars 1, is arranged a power-pulley 7, the periphery of which is preferably grooved to conform to the tire B of the motor vehicle. 65

For the purpose of leading one of the rear wheels of the vehicle to the power-wheel 7, there is provided a runway 8 formed on 70 its top with converging flanges 9 which provide an easy entrance at the lower end of the runway and direct the wheel to the power-wheel 7. This runway is preferably movably mounted to shift in the direction 75 of its length and, to this end, it operates on the rod or bar 10 connecting the longitudinal bars 1 and is tied to the bar 10 by a strap 11 which provides a longitudinally-extending way on the runway. By this arrangement, if the vehicle be supported and the wheel be turned in the direction of the arrow, Fig. 1, the wheel will move the runway longitudinally until the latter is out of the path of the wheel. To still further 80 increase this action, the upper or inner end of the runway may be supported on a crank-member 12 which is journaled at 13 in the longitudinal bars 1, the runway being secured to the crank portion by a strap 14. 85 This same arrangement will also permit the runway to be returned to its initial position, if the wheel B be rotated in the opposite direction and the upper end of the runway be brought to a position where it 90 will engage the vehicle wheel B while the latter is turning. The crank portion 12 shifts to one side of a vertical line through the turning axis 13 and thus brings the outer end of the guide 11 in contact with 95 100

the rod 10 to support the runway in the position shown in Fig. 1. When the runway shifts in the other direction, it turns on the rod 10 as a pivot.

5 A supporting means is employed which may be brought into engagement with the vehicle while the wheel of the latter is engaging the runway and the power-wheel 7. This supporting means preferably comprises an arm or member 15 having a vehicle engaging portion 16 at its upper end preferably adjustably connected to the arm 15 and, in this instance, having a crotch for engaging the axle of the vehicle and provided with a socket 17 fitting the upper end of the arm. The socket portion is provided with openings 18 and the arm is provided with openings 19, a bolt 20 being passed through one of the openings in the arm and 15 one of the openings in the socket portion to adjustably connect the vehicle engaging member to the arm 15. This adjustment is provided in order that the arm may be accommodated to different types of vehicles 20 as it is desirable that a certain pressure be maintained by the wheel B on the power-wheel.

The lower portion of the arm 15 may be provided with a shifting fulcrum on the 30 base or main frame and to this end one of the side bars 1 is provided with a slot 21 in which a pivot-pin 23 is adapted to move, the pivot-pin being carried by the arm 15. Bolted or otherwise secured to the frame 35 above the slot is a rack 24 having the teeth 25 on the under side thereof for engagement by a pawl 26 which is pivotally mounted on the pivot-pin 23 and has an extended arm 27 which acts as a weight for the purpose 40 of normally holding the pawl 26 in engagement with the rack 24. For coöperation with this extended arm 27, there may be provided a trip lever 28 pivoted at 29 to the frame and having a foot-piece 30.

45 With the end in view of preventing the shifting of the runway until the vehicle wheel has reached the pulley 7 and the supporting arm has been engaged with the vehicle, there has been provided a securing 50 means preferably in the form of a hook 31 secured to the runway 8 and adapted to engage the inner end of one of the bars 1.

While it is preferred to provide a construction which will engage only one of the 55 wheels of the vehicle, there may be provided a construction which will engage both wheels as illustrated in Fig. 5 in which four longitudinal bars 1^a are provided connected by a single hollow shaft 5^a on which two 60 power wheels 7^a are arranged. Two runways 8 are provided each leading to one of the power wheels 7^a and both supported on a crank shaft 13^a having two crank portions 12^a. Two supporting arms 15^a are arranged

upon a single pivot rod 23^a which turns in 65 two supporting arms 15^a and extends entirely across the base frame through slots therein. At each end of this pivoted rod 23^a, pawls 26^a are secured and only one of these pawls is provided with a weighted 70 arm 27^a. The other parts of the structure are substantially the same as that shown in Figs. 1, 2 and 4, as is also the operation.

The operation of the invention is as follows:—The vehicle is backed up the runway 75 8 until one of its wheels B engages the power wheel 7 and bridges the space between the latter and the ends of the runway 8. The supporting arm is then shifted so that its engaging end 16 coöperates with the axle 80 of the vehicle, the pawl 26 riding over the ratchet 24 and finally securing the pivot 23 in a fixed position. The hook 31 is then disengaged from the bar 1 and the motor of the vehicle is started to turn the wheel B 85 in the direction of the arrow. This causes the runway 8 to be shifted automatically under the action of the wheel to the position shown in Fig. 2, so that the wheel is supported by the arm 15 in engagement with 90 the power wheel 7 and transmits its motion to said power wheel. When it is desired to disconnect the vehicle from the jack, the runway 8 is shifted longitudinally until it engages the tire of the wheel, after which 95 the wheel is turned in the direction opposite to the arrow in Fig. 1, causing the runway to assume its original position where it is again held by the hook 31. The foot or trip 28 is then operated to disengage the 100 pawl 26 from the rack 24 when the arm may be shifted to release the vehicle so that the latter may travel down the runway.

An automobile-jack constructed in accordance with this invention enables the wheel 105 of a motor vehicle to directly engage a drive shaft and the runway which leads to the power wheel is automatically shifted toward and from the operative position. The vehicle supporting means engages the vehicle while the wheel of the latter is in direct engagement with the runway and the power wheel and, in this way, there is no jar imposed upon the vehicle, as the latter, after it engages the power wheel, does not 110 partake of any movement but is secured firmly in its driving position before the runway is displaced, and driving position is secured merely by the movement of the vehicle on the runway until a wheel thereof 120 engages the power pulley.

What I claim as my invention and desire to secure by Letters Patent is:

1. An automobile-jack comprising a power-wheel, a runway leading to said power-wheel 125 and movable relatively thereto, and means for supporting a vehicle while one of its wheels lies in engagement with the power-

wheel and the runway in order that the runway may be moved from engagement with the vehicle wheel without shifting the position of the wheel.

5. 2. An automobile-jack comprising a power-wheel, a runway leading to said power-wheel and shiftable under the action of a vehicle wheel in turning, and supporting means for the vehicle adapted to engage the latter 10 while a wheel of the vehicle lies in engagement with the power-wheel and the runway so that the vehicle wheel will be supported in engagement with the power-wheel after the runway has been shifted out of the path 15 of the vehicle wheel on the turning of the latter.

3. An automobile-jack comprising a power-wheel, a movable runway leading to said power-wheel, and supporting means for a 20 vehicle movable to engage the latter while a wheel of the vehicle lies in engagement with the runway and the power-wheel.

4. An automobile-jack comprising a power-wheel, a movable runway leading to said 25 power-wheel, and a vehicle supporting-arm having one end engageable with the vehicle and the other end adjustably supported to cause the vehicle engaging end to engage or disengage the vehicle.

30. 5. An automobile-jack comprising a frame, a power-wheel on the frame, a runway leading to the power-wheel and movable on the frame, an arm having its upper end provided with a portion to engage a vehicle, and its 35 other end shiftable on the frame in the direction of the length of the runway, the arm, when engaging a vehicle, lying at such an angle to the vertical that the weight of the vehicle swings the arm to throw the greater 40 amount of the weight of the vehicle on the power-wheel.

6. An automobile-jack comprising a power-wheel, a movable runway leading to the power-wheel, and a vehicle supporting- 45 arm having a shiftable fulcrum.

7. An automobile-jack comprising a power-wheel, a movable runway leading to the power-wheel, a vehicle supporting-arm having a shiftable fulcrum, and devices for 50 securing the pivot of said arm in any position to which it may be adjusted.

8. An automobile-jack comprising a power-wheel, a movable runway leading to the power-wheel, a vehicle supporting-arm 55 having a shiftable fulcrum, and devices for securing the pivot of said arm in any position to which it may be adjusted, embodying a fixed rack and a pawl carried by said arm to ride over the rack as the pivot of the arm 60 is shifted in causing the arm to engage a vehicle.

9. An automobile-jack comprising a power-wheel, a movable runway leading to the power-wheel, a vehicle supporting-arm

having a shiftable fulcrum, devices for securing the pivot of said arm in any position to which it may be adjusted, embodying a fixed rack and a pawl carried by said arm to ride over the rack as the pivot of the arm is shifted in causing the arm to engage a 70 vehicle, said pawl having an extended arm, and a device mounted on a fixed part for co-operating with the extended arm in any position to which the supporting-arm may be adjusted. 75

10. An automobile-jack comprising a power-wheel, a movable runway leading to the power-wheel, a vehicle supporting-arm having a shiftable fulcrum, and a vehicle engaging member adjustable on the arm. 80

11. An automobile-jack comprising a power-wheel, a runway leading to said power-wheel, a rod on which said runway is movably supported between its ends, a guide on said runway operating on said rod and permitting the runway to move in the direction of its length on said rod, and supporting means movable to engage a vehicle while a wheel of the latter is in engagement with the power-wheel and the runway. 90

12. An automobile-jack comprising a pair of parallel bars, a power-shaft connecting them, a grooved power-wheel on the shaft, a rod connecting the bars, a runway supported for longitudinal movement in a direction 95 transversely of the rod, and an adjustable vehicle-supporting means for supporting the vehicle while a wheel thereof is engaged with the power-wheel and the runway.

13. An automobile-jack comprising a power-wheel, a movable runway leading to the power-wheel and spaced therefrom, to permit a wheel of a vehicle to bridge the space while engaging the runway and the power-wheel, and movable vehicle-supporting means for engaging a vehicle while one of its wheels is so positioned. 100

14. An automobile-jack comprising a power-wheel, a movable runway leading to said power-wheel and spaced at one end from the latter so that a wheel of a vehicle may bridge the space while engaging the power-wheel and the runway, a movable support for that end of the runway adjacent the power-wheel acting to permit the runway to shift longitudinally away from the power-wheel when such an arranged vehicle wheel is turned, and vehicle-supporting means acting to hold the wheel toward the power-wheel when the runway is shifted. 110

15. An automobile-jack comprising a power-wheel, a movable runway leading to said power-wheel and spaced at one end from the latter so that a wheel of a vehicle will bridge the space while engaging the power-wheel and the runway, and vehicle-supporting means adjustable to engage a vehicle while a wheel of the latter is bridging the 125

space between the runway and the power-wheel and tending to move the vehicle-wheel toward the power-wheel when the runway is moved out of engagement with said vehicle-wheel.

16. An automobile-jack comprising a power-wheel, a runway leading to said

power-wheel, a rod on which said runway is movably supported between its ends, and a guide on said runway operating on said rod 10 and permitting the runway to move in the direction of its length on said rod.

DANIEL S. EVERETT.
